UNITED STATES PATENT OFFICE

HUGH M. STEPHENSON, OF FORT WAYNE, INDIANA, ASSIGNOR TO GENERAL ELECTRIC COMPANY, A CORPORATION OF NEW YORK

CURRENT REGULATING DEVICE

Application filed November 5, 1928. Serial No. 317,232.

My invention relates to current regulating devices, more particularly to variable resistances or rheostats in which the amount of resistance is varied by altering the compression of a resistance member through which the current is caused to flow, and has for its object an improved construction in a device of this character.

My invention has particular adaptation when embodied in rheostats suitable for controlling motors for sewing machines or similar light duty service especially in those rheostats which are controlled by the foot or the knee of the operator.

Among the advantageous features afforded by my invention are improved supporting means for the resistance members, an improved casing within which the resistances and the actuating means are enclosed as well as improved means for mounting the rheostat.

In carrying out my invention I have provided a casing enclosing a pair of insulating members, one of these members being fixed and the other member movable toward or away from the fixed member, and a compressible resistance unit supported on the movable member between this member and the fixed member. I have also provided resilient means between the resistance unit and the fixed member for biasing the unit toward the movable member, and an actuating member for forcing the movable member and resistance unit toward the fixed member against the action of the resilient means.

For a better understanding of my invention, reference may be had to the accompanying drawings in which Fig. 1 is a perspective view of a rheostat embodying my invention; Fig. 2 is a side elevation; Fig. 3 is a sectional view taken on the line 3-3 of Fig. 2; Fig. 4 is a perspective view of the actuating arm, while Fig. 5 is an elevation partly in section illustrating the mounting of the rheostat.

Referring to the drawings, in carrying out my invention in one form I have provided a rheostat in which the resistances and the actuating mechanism therefor are enclosed within a casing 10 formed of a pair of sheet metal stampings 11 and 12 so shaped that the

casing has the form of a letter L. The member 11 of the casing is formed preferably from a single piece of sheet metal and is bent to provide a flat bottom surface and a pair of side positions 13. The member 12 is also formed from a single piece of sheet metal bent into the shape of a letter L and is of a size sufficient to form a covering for the portion 11 of the casing. The member 12 is provided, preferably by stamping, with a plurality of apertures 14 for the purpose of dissipating heat generated in the resistance units. The side members 13, 13 are provided with rolled edges forming grooves 15, 15 and it will be observed with reference to Fig. 1 that the cover member 12 is clamped in place between these grooves.

I have provided a pair of compressible resistance units 17 and 18 supported between a fixed insulating member 19 and a movable insulating member 20. The resistance units 17, 18 are preferably formed of a plurality of small disks or plates of carbon or a suitable carbon compound, each of the resistance units thus constituting a so-called "carbon pile." The property of a resistance unit of this type whereby its electrical resistance is decreased upon compressing together the disks or plates forming the unit, is well known.

The insulating members 19 and 20 are preferably formed of a suitable heat resisting insulating material such as porcelain and are shaped so that the member 20 may be telescoped within the member 19, the latter member being provided with an enlarged recess 21 into which the member 20 is adapted to be moved.

The insulating member 20, as will be observed with reference more particularly to Fig. 3, has the shape of an inverted letter T, the vertical portion of this member extending within the recess 21 of the fixed insulating member 19. The vertical portion of the member 20 is not as wide as the recess 21, and thus spaces are formed at the sides between the vertical portion and the sides of the recess 21, these spaces being substantially filled by the resistance units 17, 18. The horizontal portion of the insulating member 20 has

a width slightly smaller than the width of the aperture 21 so that the member 20 may slide in and out of the fixed insulating member 19, while still substantially closing the opening formed by the recess 21.

5 The resistance units 17 and 18 rest upon metallic disks 22, 23 which in turn are secured to the insulating member 20 by means of suitable screws 24, 25, the screws serving 10 as terminals whereby electrical connections may be made to the resistance units 17, 18. A pair of metallic disks 26, 27 provided with projections 28, 29 rest upon the upper ends 15 of the resistance units 17 and 18. A flat leaf spring 30 in the shape of a bow rests upon the projections 28 and 29 of the metallic disks 26, 27 and at its upper side engages the fixed insulating member 19. A helical compression spring 31 is supported between the insulating 20 members 19 and 20, being mounted in an aperture provided for this purpose in the vertical portion of the insulating member 20. The fixed insulating member 19 is provided with an aperture 32 extending horizontally 25 through the upper part of the member 19. The aperture 32 is substantially oval in section and serves to hold a tubular metallic member 33 having a depending tab 34. The ends of the tubular member 33 are threaded 30 to contain machine screws 35, 36 which are passed through the side portions 13 of the casing member 11. It will be observed that the depending tab 34 on the tubular member 33 projects into the lower portion of the oval-shaped aperture 32 and prevents the tubular member 33 from turning within this aperture while the screws 35, 36 are being threaded into or out of the member 33. In order to 35 limit the movement of the member 20 and to 40 prevent disassembly or disarrangement of the parts of the resistance units, the member 20 is provided with a transverse slot 37 and the fixed insulating member 19 has secured therein a rivet 38 extending into the slot 37. 45 It will thus be seen that the movement of the member 20 relative to the fixed member 19 is limited to the length of the slot 37.

50 In order to force the movable insulating member 20 and the resistance units 17, 18 into the fixed insulating member 19 against the compression of the springs 30 and 31, I have provided an actuating arm 40 shown more clearly in Figs. 2 and 4. The arm 40 has formed at one end an outwardly projecting, 55 rectangularly shaped portion 41 and at the other end a tab 42 bent upwardly at right angles to the arm 40. Between its two ends the arm 40 is provided with an upward bend 43 forming a groove in the under side of the 60 arm 40, this groove serving as a bearing on a rod 44 secured in the casing 10 between the side portions 13 of the casing member 11. The tab 42 of the arm 40 is adapted to engage a recess 45 in the lower surface of the 65 movable insulating member 20. It will be

observed with reference more particularly to Fig. 1 that the two portions 11 and 12 of the casing 10 do not meet at the outer or right-hand end of the rheostat and an aperture 46 is thus formed through which the outwardly projecting portion 41 of the arm 40 extends. 70

The member 12 of the casing 10 is provided with a pair of openings 48, 49 and the arm 40 with a pair of openings 50, 51, the latter openings being so located as to be directly under the openings 48, 49 in the casing member 11 so that screws may be inserted downwardly through the openings 48, 50 and 49, 51 respectively and through apertures 51a, only one of which is shown, in the bottom of the casing 10 in order to secure the casing to a suitable support such as the framework of a sewing machine. The bottom of the casing 10 is provided at the rear or left-hand end, as in viewing Fig. 2, with a pair of projecting caps 52 and 53 and at the front or right-hand end with a pair of resilient members 54, preferably of rubber. The projecting caps 52, 53, are adapted to be removed in order to facilitate the connection of the electrical conductors to screws 24 and 25, and after being replaced serve in conjunction with the members 54 as supporting feet for the rheostat. An aperture 55 is provided in each of the side portions 13 to allow for the insertion of a resilient 80 insulating bushing 55a which is sleeved over the electrical conductor 56 attached to the terminals 24, 25 of the resistance units 17, 18, the two apertures 55, 55 being provided to allow for right or left hand assembly of the 85 electrical connections. The resilient foot members 54 and the insulating bushing 55a are preferably identical in construction, these members being described and claimed in the 90 copending application of Marvin L. Norris, Serial Number 198,855, assigned to the same 95 assigned as this invention. The above identified application is a division of another copending application of Marvin L. Norris, Serial Number 98,879, also assigned to the 100 same assignee as this invention. An aperture 57 shown in Fig. 5 is provided in the bottom 105 of the casing 10 at a point substantially at the center of the rear or lower left-hand edge of the casing, this aperture constituting a screw-slot enabling the bottom wall of the casing to be slid under the head of a screw 58 which may be inserted in the frame or support to which the rheostat is to be attached. The 110 aperture 57 is formed by punching in a small 115 portion of the metal forming the bottom wall of the casing 10, this punched-in portion being then bent upwardly to partly surround and form a supporting tab 59 for the conductor 56, as is shown clearly in Fig. 5. When 120 it is desired to mount the rheostat on a supporting member such for instance as the framework of a sewing machine, the bottom wall of the casing is pushed under the head of the screw 58 which has preferably been 125 130

screwed for part of its length into the supporting framework, care having been taken that sufficient room is left under the head of the screw to allow for the insertion thereunder of the bottom wall of the casing 10, as is clearly shown in Fig. 5. Additional screws, not shown, are then inserted through the apertures 48, 49, 50, 51, 51a, 51a and screwed into the supporting framework, the heads of the screws engaging the bottom wall of the casing 10 around the apertures 51a, 51a.

The outwardly projecting portion 41 of the arm 40 is provided with threaded apertures 60 and it is contemplated that if or when the rheostat is to be used for knee operation, a suitable knee-engaging member, not shown, will be attached to the portion 41 by means of screws threaded into the apertures 60. When the rheostat is used for foot operation, it will be placed preferably on the floor and the foot of the operator will directly engage the outwardly projecting portion 41.

In operation, my rheostat preferably is attached to the frame or cabinet of a sewing machine or the like, if knee operation is desired, or to the floor if it be desired to actuate the rheostat by the foot of the operator. The operator, by pressing on the outwardly projecting portion 41 of the arm 40, either through the medium of a suitable knee-engaging member as hereinbefore described, or directly by the foot, causes the arm 40 to move about the shaft 44, whereupon the rear end of the arm 40 forces the movable insulating member 20 into the recess 21 against the compression of spring 31. The resistance units 17, 18 will be forced against the flat spring 30 and the carbon disks or plates of the resistance members will thus be compressed. A slight slip or wiping action will occur between the spring 21 and the projections 28, 29 of the metallic members 26, 27 thereby insuring a good electrical contact between the ends of the resistance units 17, 18 and the spring 21. The resistance units 17, 18 are thus connected in series in the circuit to be controlled, the spring 21 serving both as means for electrically connecting the resistance units in series and as a bias for returning the resistance units to their starting position. The operator by exerting a greater or lesser pressure on the arm 40 will cause the resistance of the units 17, 18 to be decreased or increased and the speed of the motor to be governed will be varied accordingly.

While I have described my invention as embodied in concrete form and operating in a specific manner in accordance with the provisions of the patent statutes, it should be understood that I do not limit my invention thereto, since various modifications thereof will suggest themselves to those skilled in the art without departing from the spirit of my

invention, the scope of which is set forth in the annexed claims.

What I claim as new and desire to secure by Letters Patent of the United States, is:

1. A rheostat comprising an L shaped casing, an insulating member fixedly mounted in one branch of said casing, said fixed member being provided with a recess, a second insulating member slidably mounted within said recess, a compressible resistance unit mounted in said recess, one end of said unit being supported upon said slidible member, a spring between the other end of said unit and said fixed member, and an actuating arm for said slidible member, said arm being pivotally mounted within the other branch of said casing.

2. A rheostat comprising a casing, a member made of electrically insulating material secured in said casing, said member being provided with a recess, a second member made of electrically insulating material slidably mounted in said recess and loosely fitting therein, means for moving said second member in said recess toward and away from said first member, a pair of compressible resistance units in said recess mounted on opposite sides of said second member having their inner ends substantially flush with the inner end of said second member, and resilient means between the inner ends of said members forming an electrical connection between the inner ends of said resistance units.

In witness whereof, I have hereunto set my hand this 2nd day of November, 1928.

HUGH M. STEPHENSON.
